FIRE ALARM BOX

Robert B. Long, Dayton, Ohio

Application October 2, 1935, Serial No. 43,214

6 Claims. (Cl. 177—379)

This invention relates to a fire alarm signal box and more particularly to a removable hand cuff attachment and the mechanism associated therewith, adapted for use in a fire alarm box.

An object of this invention is to provide such an attachment for fire alarm boxes that prevents the reporting of a false alarm without determining who turned in the fire alarm.

Another object of this invention is to provide a device that is cheap, efficient and dependable.

Another object of this invention is to provide a device that will not permit the reporting of the fire by use of mechanical devices instead of manual manipulation.

With the above primary and other incidental objects in view, as will more fully appear in the specification, the invention consists of the features of construction, the parts and combinations thereof, and the mode of operation, or their equivalents, as hereinafter described and set forth in the claims.

Fig. 1 is a perspective view showing the fire alarm box door immediately after the cuff has been removed.

Fig. 2 discloses an inside view of the door embodying one type of mechanism for releasing the cuff.

Fig. 3 is a fragmentary view of a portion of the mechanism at the time that the mechanism is in cuff releasing position.

Figs. 4, 5, and 6 are detail views of the cuff mechanism, Fig. 6 being shown in section.

Fig. 7 discloses the preferred embodiment of the cuff releasing dial and the parts associated therewith.

Fig. 8 is a sectional view taken substantially on the line 8—8 of Fig. 7.

Fig. 9 is another modification of the cuff releasing mechanism that may be mounted on the inside of the door.

Fig. 10 shows another modification of a dial that may be used instead of the mechanism shown in Figs. 7 and 8.

Fig. 11 is a fragmentary, sectional view of another safety device embodied in the modifications shown in Figs. 2 and 9.

Fig. 12 discloses another modification of the cuff mechanism.

Fig. 13 is a fragmentary sectional view of one side plate and parts associated therewith, taken substantially on the line 13—13 of Fig. 12.

Fig. 14 is a fragmentary view of the actuating mechanism shown in Fig. 9 when moved to other positions.

In the conventional fire alarm boxes there is

found a fire alarm signal mechanism that is actuated when reporting a fire. Most of the mechanism is generally located in a housing provided with a door having a lever or suitable actuating mechanism extending therethrough, so that the fire may be reported without actually opening the door. This however varies, as in some installations it is necessary to open the door.

In the accompanying drawings the door 20 is provided with a housing or enclosure 22 having an opening at its bottom receiving a handcuff unit 24 held in position by suitable pins 26. The handcuff unit 24 disclosed in Figs. 1, 4, 5, and 6 is a removable closure. It is provided with an opening 28 and is located in the opening below the closure 22. The unit 24 has a pair of gripping jaws 32 and 34 that are released by a suitable mechanism to be described later, so as to grip the wrist of the operator as he turns the knob mechanism 40, whereby the one reporting the fire carries the cuff unit 24 on his wrist until the gripping jaws 32 and 34 are released, as fully described in my copending application Serial Number 607,116, filed April 23, 1932, for a Fire alarm box attachment, now Patent Number 2,020,279, granted Nov. 5, 1935.

Referring to Fig. 2, wherein the inside of the door has been disclosed, the actuating mechanism includes a lever 42 pivotally mounted on the door at 44. This lever 42 supports a pin 46 upon which is rotatably mounted a sleeve 48 supporting a cam 50 fixedly attached thereto. As the knob 40 rotates the cam 50 in a counter-clockwise direction through a suitable driving mechanism which will be described later, the lobe 52 engages a stationary pin 54 which urges the cam 50 to actuate the lever 42 in a clockwise direction as viewed in Figs. 2 and 3 about the pivot 44 against the spring 56. As the cam 50 is rotated in a counter-clockwise direction it releases detent member 60 pivotally mounted at 62, permitting the spring 64 to actuate member 66 in a counter-clockwise direction, as viewed in Fig. 2, thereby causing the projection 66 to release the cuff, as disclosed in my copending application.

In some types of boxes it is necessary to open the door in order to reset the fire alarm signal transmitting mechanism. In others the opening of the door automatically transmits the signal. In the modification disclosed in Fig. 2, the latch 72 normally opened by the insertion of a key in the lock 74 shown on the front side of the door, as viewed in Fig. 1, or by any suitable

handle or latch is automatically released when the cam 50 is actuated, so as to release the detent 60. This is accomplished by a bell crank lever 76 pivotally mounted at 78 having one arm 80 mounted for engagement with the projection 84 of member 60, so as to rotate the bell crank member 76 in a counter-clockwise direction, as viewed in Fig. 2, causing the pawl 82 seated in a suitable recess in member 72 to release it, thereby permitting the door to be swung into open position whenever the handcuff unit 24 is released.

If the signal is transmitted in response to the release of the cuff unit 24, the door is automatically unlocked to permit the firemen to reset the box. If a system is used wherein the box must be opened when relaying the signal, the cuff unit 24 will automatically lock itself on the reporter's wrist whenever the knob 40 is actuated to open the door.

As may be best seen in Fig. 5, the jaws 32 and 34 preferably of tool resisting material, have been lined with heat insulating material 86 and 88 such as vulcanized rubber, so that if the reporter of a fire happens to report a fire during extremely cold weather and his arm happens to be moist, the jaws will not freeze to his arm. This is found necessary for the safety of those reporting the fires. A tubular sleeve 90 is mounted below the opening 28 and is equipped with a resiliently biased closure 92 normally in closed position to prevent birds, bees and the like from forming nests within the housing 22. Furthermore, the sleeve 90 and the closure 92 keep dust and foreign matter from accumulating in the box.

It is conceivable that a person might insert a suitable object, such as a short pipe, a metallic casing in the opening 28, or a pair of clamps engaging the jaws to prevent movement thereof, and then pass the arm through this opening to turn in a false fire alarm, the jaws 32 and 34 engaging the object, the operator slipping his arm through the opening and escaping without the cuff unit 24. In order to overcome this difficulty a lever 94 pivoted at 96 and biased in a counter-clockwise direction, as viewed in Fig. 5, by a suitable spring 98 normally projects a short distance into the opening 28 and has limited normal movement. This member 94 is preferably located below the knob or dial side of the fire alarm system. Referring to Fig. 11, a detent 100 integral with member 94 is aligned with the opening 102 and with a pawl 104, so that as member 94 is actuated in a clockwise direction, as viewed in Fig. 5, the detent 100 will urge the pawl 104 to the left, as viewed in Fig. 11. The detent 104 pivotally mounted at 106 and urged in a counter-clockwise direction, as viewed in Fig. 11, is provided with an extension 110 that limits the movement of a pivotally mounted arm 112 to prevent the operation of the fire signalling device and the release of the handcuff when thus locked. By referring to Fig. 2, the latch arm 112 is pivotally mounted at 114 and provided with a dog 116 normally seated against member 58. As best seen in Fig. 2, the latch 112 is urged in a counter-clockwise direction by a spring 118. Whenever the extension 110 of the pawl 104 locks member 112 so as to prevent it from rotating in a clockwise direction about the pivot 114, it is impossible to rotate the cam 50 and to actuate the parts associated therewith. Thus, it will be seen, that if the operator inserts his arm into the opening 28, member 94 may move a limited distance without locking the mechanism. It has

been found that normally a person will actuate member 94 a limited distance but will not lock the mechanism. Furthermore, if the operator should perchance lock the mechanism momentarily in attempting to rotate the knob 40, the operator would in all probability release the pressure upon member 94 sufficiently long to permit the parts to operate. On the other hand, if a person tampering and attempting to turn in a false alarm inserts a pipe or some other foreign article into the opening 28 so as to prevent the jaws 32 and 34 from snapping into closed position, such a person would in all probability actuate member 94 sufficiently far to lock the mechanism. Certainly this would be the case in the event that instead of a pipe, clamping jaws were inserted in opening 28. This would prevent the jaws 32 and 34 to close upon the operator's arm. The clamping jaws thus inserted would actuate member 94 in a clockwise direction, as viewed in Fig. 5, so as to lock the mechanism. Member 94 is provided with a rubber facing 120 for the same reason as the facing is placed upon the jaws 32 and 34.

When a knob like that disclosed in my copending application Serial No. 607,116 is used, it is conceivable that a person desiring to turn in a false alarm might remove his belt and use it to drive the knob without inserting his arm into the opening 28, thereby defeating the purpose of the cuff unit 24, which would permit the violator to escape without any obstructions. To eliminate this difficulty the knob 40 is rotatably mounted upon a pintle 122 fixedly attached to member 42. The knob is fixedly attached to a gear 124 also rotatably mounted upon the pintle 122 and meshing with a gear 126 fixedly attached upon a stub-shaft 128 journaled in a shield 130 and driving a gear 132 meshing with a gear 134 fixedly attached upon a tubular sleeve 136 driving the cam 50. The shield 130 is mounted for vertical movement in the guides 138 fixedly attached to the wall of the door 20, so that the shield may have substantially vertical movement with the cam 50. The face of the shield 130 is cut away at 140 so as to expose oppositely disposed portions of the knob 40. As may best be seen by referring to Fig. 8, the knob 40 is preferably split and provided with an annular groove 142 in the periphery thereof, into which extend diametrically arranged members 144 and 146 which obstruct the contour of the knob assembly 40. Members 144 and 146 are fixedly attached to the shield 130 and move therewith.

Referring to the modification disclosed in Figs. 7 and 8, the shield for the gears is supported upon member 122 and moves up and down through a slightly arcuate path in response to the reporting of a fire. Referring to Fig. 9 for example, the cam 50 is precluded from moving downwardly by a pin located below this cam. This is more fully explained in the Long Patent No. 2,020,279. However, as the cam 50 is rotated the lobe 52 engages the pin 54, at which time the notch in the cam below the pivot 46 is rotated sufficiently so as to register with the pin below the cam, allowing the cam to move downwardly. As the cam moves downwardly, the shield and the gears mounted in the shield also move downwardly in unison with the cam 50. In the Long patent the cam 40 mounted upon member 37 was rotated by turning the knob 10. In the present modification the knob 10 has been removed and the gear 134 substituted therefor. This gear meshes with the gear 132 fixedly attached to the gear 75

126, meshing with the gear 124 fixedly attached to the knurl knob 40, so that as the operator rotates the knurl knob 40 the cam 50 in the application is rotated through the train of gears. 5 From the foregoing it may readily be seen that it is practically impossible to insert a cord, a belt or any type of a string so as to actuate the knob 40.

In order to preclude the use of a stick or some other rigid member inserted through the opening 28 to engage the exposed portions of the knob 40, a ledge or shelf 150 fixedly attached to the support of the guides 138, obstructs the path between the knob 40 and the opening 28. Thus, 15 it will be seen, that in addition to preventing the use of a belt and the like for falsely reporting a fire, the use of a stick or any other rigid member for the operating of the knob 40 is prevented.

In Fig. 10 a knob 150 has been shown instead 20 of the knob 40 and the gears driven thereby together with the knob. This knob 150 is provided with a substantially bell-shaped locking member 152 pivotally mounted at 154 and normally urged in a counter-clockwise direction by a spring 156 25 as viewed in Fig. 10. In normal position the arcuate arm 158 of the bell crank lever 152 is flush with the periphery of the knob, a portion of which has been cut away to accommodate the arcuate surface of member 158. The other arm 30 of the bell crank lever 152 normally engages a notch in the pintle 122 so as to prevent rotation of the knob 152 without the fingers of the operator actuating the bell crank lever 152 in a counter-clockwise direction from the full line position 35 to the dot-dash position in Fig. 10. When the operator actuates the bell crank lever from the full line position to the dot-dash position the arm is released from the notch in member 122 so as to permit free rotation of the knob 152. 40 If a belt is used by the operator to turn in a false alarm, such a belt will not depress the arcuate arm 158 sufficiently to release the latch, thereby preventing the reporter of a false alarm from manipulating the fire alarm signal system 45 by use of a belt, cord, string or the like.

In the modification disclosed in Figs. 2 and 3 the extension 160 of member 42 is used to actuate the signal transmitting mechanism which has not been shown. It has been found that various 50 types of fire alarm boxes are in use, some of which may have the signal transmitting mechanism located elsewhere. In order to provide 55 actuating mechanism that is adaptable to a great variety of boxes the mechanism disclosed in the modification in Fig. 9 may be used.

In this modification in addition to member 42 being used as shown in the modification in Fig. 3, a member 160 is pivotally mounted at 170 and pivotally supports a latch 162 at 164. A 60 member 168 provided with a slot 169 is also mounted upon the pivot 170; but may move through a limited longitudinal movement. Member 168 is constantly urged to the right, as viewed in Fig. 14, by a spring 171, having one end 65 attached to a stud 173 fixedly attached to member 168 and the other end mounted upon the stud 175 fixedly attached to member 160 and projecting through a slot 177 in member 168, the stud 175 cooperating with the pivot 170 to 70 permit member 168 to have a predetermined movement with respect to its support 160. A stud 179 carried by member 168 is engaged by a cam 180 having its center at 170 and held in a rigid position by a screw 184 threadedly engaging a bracket 181 fixedly attached to the sup-

port of the mechanism. As members 160 and 168 are actuated from the dot-dash position shown in Fig. 14 to the full line position, the cam 180 retracts or urges member 168 to the left, as viewed in Fig. 14 against the force of the 5 spring 171 to release the latch 162 when the actuator, which has not been shown, has been moved to its full stroke. Members 160 and 168 may be actuated in a clockwise direction about the pivot 170 by an adjustable link 172 pivotally mounted 10 at 174 to member 60.

By adjusting the length of the arm 172, which is preferably made of two sectors, one of which is provided with a slot 176, the position of member 168 may be further adjusted. In addition 15 to member 162 actuating the signal transmitting device, the arm 190 may be provided with a suitable signal actuating member 194 that is preferably mounted on member 190. When a type box 20 is used where member 194 actuates the signal transmitting device, the rod 172 may also be adjusted to satisfy the requirements of the system. In order to keep member 168 confined within a predetermined path, a retaining member 200 fixedly attached at 202 and 204 to member 160 25 limits the transverse movement of the arm 168.

In resetting the above described mechanism, member 60 is preferably rotated in a clockwise direction by a suitable wrench or tool, not shown, which rotates member 160 in a counterclockwise 30 direction about the pivot 170 into the dot-dash position shown in Fig. 14. The latch 162, which was released during the clockwise movement of member 160, may then be actuated into the dot-dash position shown in Fig. 14. 35

Referring to Figs. 12 and 13 another modification has been shown, disclosing a device complementing 120 in preventing the manipulation of the fire alarm signal system without the cuff 40 engaging the wrist of the operator. It is conceivable that a person having a thorough knowledge of the operation of the device may hold his arm rigidly against the free ends of the jaws of the cuff shown in Fig. 5. If sufficient force is applied to the jaws, the jaws may be hindered 45 from engaging the operator's arm and thereby permitting the operator to slip his arm and hand through the cuff. A member 200 shown in full line position in Fig. 12 is slidably mounted in the casing of the cuff underneath member 94, as 50 shown in Fig. 13. This member 200 supports a pin 202 projecting through a slot 204 diagonally arranged in member 206, pivotally mounted upon the pivot 96. If member 200 is actuated to the left, as viewed in Fig. 12, into the dot-dash 55 position, the pin 202 cooperating with the slot 204 actuates members 206 in a clockwise direction about the pivot 96, causing the detent 208 to actuate member 104 shown in Fig. 11 into locking engagement to lock member 112, thereby 60 preventing the release of the signalling mechanism. Member 200 is normally urged to the right, as viewed in Fig. 12, by a suitable spring 210. 65

From the foregoing it is apparent that if an operator tries to insert a cylindrical member to prevent the cuff from engaging the wrist of the violator, member 94 will in all probability be rotated in a clockwise direction so as to lock the mechanism, preventing the transmission of the 70 signal. Likewise, if the operator should attempt to urge his arm against the ends of the jaws he would actuate member 200 into dot-dash position shown in Fig. 12, thereby preventing the reporting of the signal. In either event, the cuff 75

would not be released and the false report would not be transmitted. Anyone attempting to report a fire would normally insert the arm through the opening 28 without actuating members 94 and 5 200 to lock the mechanism. If, perchance, the mechanism would be momentarily locked, the reporter of a fire in attempting to manipulate the lock would in all probability move the arm into such position as to release the mechanism, there- 10 by permitting the reporting of the fire. Thus, it may be readily seen that a person attempting to defeat the operation of the cuff would be pre- 15 cluded from operating the fire alarm mechanism, whereas a person desiring to report a fire, if he accidentally locked the mechanism, would in all probability release the locking mechanism in attempting to actuate the fire signal transmitting device.

From the above description it will be apparent 20 that there is thus provided a device of the character described possessing the particular features of advantage before enumerated as desirable, but which obviously is susceptible of modification in its form, proportions, detail construction and ar- 25 rangement of parts without departing from the principle involved or sacrificing any of its advan- tages.

While in order to comply with the statute, the 30 invention has been described in language more or less specific as to structural features, it is to be understood that the invention is not limited to the specific features shown, but that the means and construction herein disclosed comprise the preferred form of several modes of putting the 35 invention into effect, and the invention is therefore claimed in any of its forms or modifications within the legitimate and valid scope of the appended claims.

Having thus described my invention, I claim:

40 1. A device for identifying the operator of a fire alarm transmitting device including a combination with means for operating the signal transmitting device, said means including manually operable split knob portions having an annular 45 peripheral groove intermediate said portions and diammetrically arranged stationary members extending into said groove, said stationary members obstructing a portion of the periphery of the knob while leaving the remainder of the 50 knob unobstructed, an enclosure for the signal transmitting device having an opening, a contractible handcuff detachably mounted contiguous to said opening through which the operator's hand may be inserted to operate said knob, means 55 for actuating and locking the handcuff in contracted position, means for releasably supporting the handcuff relative to the closure opening and means controlled incident to the operating of the transmitting device for releasing the handcuff 60 and effecting through said actuating means contraction thereof upon the arm of the operator.

2. A device for identifying the operator of a fire alarm transmitting device including a combination with means for operating the signal transmitting device, including a transferable knob actuating the signal transmitting device, said knob being mounted within a movable shield 65 limiting the exposed portions thereof permitting the knob to be operated manually and transfer- 70 ring therewith, an enclosure for the signal transmitting device having an opening, a contractible handcuff detachably mounted contiguous to said opening through which the operator's hand may be inserted to operate said knob, means for actu- 75 ating and locking the handcuff in contracted po-

sition, means for releasably supporting the handcuff relative to the closure opening and means controlled incident to the operating of the transmitting device for releasing the handcuff and effecting through said actuating means contraction thereof upon the arm of the operator, said shield deterring the use of foreign objects in attempting to actuate the fire alarm transmitting device without inserting the hand through the handcuff.

3. A device for identifying the operator of a fire alarm transmitting device including a combination with means for operating the signal transmitting device, including a manually rotatable knob, and an obstruction partially enclosing the knob leaving at least one side exposed, said obstruction preventing the unauthorized rotation of the knob by a flexible member such as a cord or belt but permitting manual rotation of the knob, an enclosure for the signal transmitting device having an opening in the bottom, a contractible handcuff detachably mounted contiguous to said opening through which the operator's hand may be projected upwardly to operate said knob, means for actuating and locking the handcuff in contracted position, means for releasably supporting the handcuff relative to the closure opening and means controlled incident to the operating of the transmitting device for releasing the handcuff and effecting through said actuating means contraction thereof upon the arm of the operator.

4. A device for identifying the operator of a fire alarm transmitting device including a combination with means for operating the signal transmitting device, including a grooved knob and speed reducing gears driven by the rotation of the knob for increasing the effectiveness of the means projecting into the groove of the knob for obstructing a portion of the periphery with the remainder unobstructed, an enclosure for the signal transmitting device having an opening, a contractible handcuff detachably mounted contiguous to said opening through which the operator's hand may be inserted to operate said knob, means for actuating and locking the handcuff in contracted position, means for releasably supporting the handcuff relative to the closure opening and means controlled incident to the operating of the transmitting device for releasing the handcuff and effecting through said actuating means contraction thereof upon the arm of the operator.

5. In a device for identifying the operator of a false alarm transmitting device having a cuff, a cam mounted for oscillatory and transverse movements, a shield, means for nonrotatably mounting the shield for transverse movement in unison with the cam, and a cam actuating mechanism mounted within said shield for actuating said cam, said cam actuating device including a knob partially enclosed and shielded by the shield, said knob having a portion extending beyond the shield, means for interconnecting the knob to the cuff through said cam so that the movement of the knob actuated through the shield controls said cuff.

6. A device for identifying the operator of a fire alarm transmitting device including a combination with the signal transmitting device, an enclosure for the signal transmitting device having an opening, a contractible handcuff detachably mounted contiguous to said opening through which the operator's hand may be inserted into said enclosure to operate the signal transmitting

device, means for actuating and locking the handcuff in contracted position, means for releasably supporting the handcuff relative to the closure openings, means controlled incident to the operation of the transmitting device for releasing the handcuff and effecting through said first means contraction thereof upon the arm of the operator, and means mounted in association

with the handcuff, said means having normally a free ineffective range of movement permitting the operation of said transmitting device and mechanism for locking the transmitting device when said movement of said means exceeds the 5 normal free ineffective range.

ROBERT B. LONG.

CERTIFICATE OF CORRECTION.

Patent No. 2,106,849.

February 1, 1938.

ROBERT B. LONG.

It is hereby certified that error appears in the printed specification of the above numbered patent requiring correction as follows: Page 4, second column, line 39, claim 4, before "means" insert the word and comma knob, ; and that the said Letters Patent should be read with this correction therein that the same may conform to the record of the case in the Patent Office. Signed and sealed this 15th day of March, A. D. 1938.

(Seal)

Henry Van Arsdale,
Acting Commissioner of Patents.
